METHOD OF AND APPARATUS FOR FACILITATING
THE BUILDING OF WALL STRUCTURES
Filed May 3, 1927

INVENTOR

Albert N. Young

By Julian H. Hendig, Atty.

UNITED STATES PATENT OFFICE.

ALBERT N. YOUNG, OF CASTLE SHANNON, PENNSYLVANIA.

METHOD OF AND APPARATUS FOR FACILITATING THE BUILDING OF WALL STRUCTURES.

Application filed May 3, 1927. Serial No. 188,571.

My invention relates to a method of building wall structures particularly of the block and mortar type, and apparatus for facilitating the building of such structures.

5 One object of my invention is to provide a putlog for the scaffolding that may be anchored in the wall as it is being built and to thereby eliminate the inner uprights usually required immediately adjacent the wall structure.

10 Heretofore, in building a block and mortar wall it has been customary to build a scaffolding upon which the mason works by placing inner uprights immediately adjacent the wall and outer uprights spaced several feet from the wall and by joining them with horizontal putlogs, bolted or nailed to the uprights. The putlogs serve to support the horizontal boards or planks constituting 15 the platform upon which the mason works.

An object of my invention is to provide 20 a putlog that may be temporarily anchored in the space between the blocks of the wall for supporting its inner end and to thereby 25 eliminate the usual inner uprights. Since there are a large number of uprights required for the inner portion of the scaffolding, according to the old style of construction, quite a saving in labor and material 30 cost is rendered possible by the use of my improved putlogs and method of operation.

A further object of my invention is to reduce the material necessary for scaffolding and to reduce to a minimum the time required for erecting and taking down the 35 scaffolding.

These and other objects that will be made apparent throughout the further description of my invention are attained by means of the 40 process and apparatus hereinafter described and illustrated in the accompanying drawings wherein,

Fig. 1 is a perspective view of a scaffolding in which my improved putlog is employed; 45 Fig. 2 is a perspective view of my improved putlog;

Fig. 3 is a transverse vertical section through a wall under construction and with 50 which my improved scaffolding putlog is employed;

Figs. 4 and 5 are elevational and sectional views, respectively, of a fragment of a wall on an enlarged scale, illustrating the application of my improved putlog thereto.

55 Referring to the drawings and particu-

larly to Fig. 1 which shows a scaffold applied to a wall structure, a brick and mortar wall is illustrated in the process of construction. The wall in this instance is a brick veneer wall comprising vertical wooden studding 6 upon which board sheathing 7 is nailed. A single layer of brick 8 is laid upon the foundation 9 in the usual manner up to the elevation of the first platform. At this level a plurality of horizontally disposed putlogs 12 are laid upon the row 11 of the brick wall.

The improved putlog 12 comprises a metal bar of T-shape, commercially known as a T-bar, which may have the flanges or webs 70 angularly cut at one end to form a pointed bar, as shown in Fig. 2. The bar is perforated adjacent the ends for receiving retaining nails in a manner to be hereinafter described.

75 As shown in Figs. 1, 4 and 5, the putlog is placed with its flat face upon the center of a brick, and the web 13 is disposed in the space 14 between the adjacent ends of bricks 15 and 16, usually occupied by the mortar. 80 The pointed end of the putlog may be driven partially into the wooden sheathing 7 as indicated in Fig. 5 in order to support it initially upon the sheathing until the mortar surrounding the brick directly beneath the 85 putlog hardens sufficiently to sustain the weight of the scaffolding without being displaced.

The outer ends of the putlogs are supported upon the horizontal ledger boards 17 that 90 are nailed to the uprights 18, and are secured to the uprights 18 by nails 19 inserted in holes 21 in the webs or flanges of the putlogs.

A platform comprising planks 22 is placed 95 upon the putlogs which are preferably spaced about four feet apart and upon this platform the mason operates until the wall reaches a level that necessitates a second platform.

100 In Fig. 3 I have shown a wall comprising a foundation wall composed of cement blocks, and a brick wall 11 of the veneer type shown in Fig. 1. Two sets of putlogs are shown, the lowermost set remaining as a part of the scaffolding and the planks 22 of the platform are disposed on the upper set of putlogs. As many sets of putlogs may be employed as the height of the wall requires.

When the wall is completed and the scaffolding is no longer necessary, the platform is shifted to a lower set of putlogs and the upper set withdrawn from the wall. The 5 spaces between the bricks formerly occupied by the putlogs are filled with mortar. The putlogs are thus successively removed and the spaces occupied thereby are filled with mortar. Since the webs of the putlogs 10 loosely fit within the usual mortar space between the blocks, the places formerly occupied by the putlogs cannot be detected after they have been filled with mortar.

As shown in Fig. 3, the uppermost putlog 15 is shown as applied to the sheathing for supporting the carpenter's scaffold. It will be noted that the portion of the putlog is reversed with respect to the putlogs beneath it, and that the end of the web, 13, is cut 20 away as shown in Figs. 1 and 2, leaving a flat flange which may be inserted through the space between the sheathing boards and pinned in place by tapered pins, 25, which are inserted through the holes 26 and which 25 engage the rear face of the sheathing.

While I have shown the improved putlog applied to a wall composed of cement blocks and brick veneer, it is obvious that the invention is equally applicable to solid 30 brick, stone, tile or other walls.

Where no sheathing is used the inner ends of the putlogs may project beyond the inner side of the wall and may be temporarily nailed to the uprights by nails inserted 35 through holes 24 in the pointed ends of the putlogs and spacing blocks placed between the vertical flange thereof.

By reason of the use of my improved putlog the cost of scaffolding is very materially 40 reduced, and since the putlogs are made of metal, they are practically indestructible and may be used over and over. They occupy less space than the usual wooden putlogs and may be conveniently carried and 45 stored in limited space.

By anchoring the inner ends of the putlogs in the wall, a rugged and safe scaffolding is produced requiring no diagonal bracing of the outer uprights, thus materially 50 reducing the lumber required.

It is obvious that bars having other shapes, such as angle bars, or bars having all but the vertical web cut away at the ends, may be substituted for the T-bar illustrated 55 and my invention is not limited to the specific bar construction illustrated. Any bar that may be placed within the usual mortar space without necessitating displacement of the block lies within the contemplated scope 60 of my invention.

While I have illustrated certain embodiments of my invention, it will be apparent to those skilled in the art that various changes, modifications, substitutions, additions and omissions may be made in the ap-

paratus illustrated without departing from the spirit and scope of my invention, as set forth in the appended claims.

I claim as my invention:

1. A fabricated metal T-bar adapted for 70 use as a horizontal putlog for scaffolding, with its flat side horizontal, characterized by having its vertical web cut down at both ends and having perforations for receiving nails near the ends of all webs, as well as a 75 plurality of spaced intermediate perforations for adapting the bar to general use in several different ways in scaffolding.

2. A putlog comprising a fabricated structural-metal bar having webs at an angle to each other, characterized by having at least one end cut down to provide a single horizontal flange-extension adapted to fit into horizontal cracks in a wall and having perforations for receiving nails near the ends 80 of all webs suitable for receiving nails.

3. A putlog comprising a fabricated structural-metal bar having webs at an angle to each other, characterized by having one end pointed, one of the webs being cut entirely 90 away at the other end, said bar having perforations at each end thereof suitable for receiving nails.

4. A fabricated metal T-bar adapted for 95 use as a horizontal putlog for scaffolding, with its flat side horizontal, characterized by having its vertical web cut down at at least one end and having perforations for receiving nails near the ends of all webs as well as a plurality of spaced intermediate 100 perforations for adapting the bar to general use in several different ways in scaffolding.

5. A putlog comprising a fabricated structural-metal bar having webs at an angle to each other, characterized by having at least one end cut down to provide a single horizontal flange-extension adapted to fit into horizontal cracks in a wall and having perforations for receiving nails near the ends of all webs, as well as a plurality of spaced 110 intermediate perforations for adapting the bar to general use in several ways in scaffolding.

6. A structural-metal bar adapted for use 115 as a horizontal putlog for scaffolding, with a flat horizontal web, characterized by having at least one vertical web, the vertical web being cut back at different distances at the two ends of the bar, the horizontal 120 web being flat to its very ends to provide flat web-extensions either of which is adapted to fit into a horizontal crack in a wall, the two web-extensions being adapted, by reason of the dissimilar cutting of the ends of the vertical web, to extend different distances into the crack in the wall, the horizontal web-extension which is adapted to extend the further in the wall being provided with a perforation for receiving a pin 125 for preventing accidental withdrawal of the 130

bar from the crack, the bar having also other perforations so spaced that, whichever end is inserted for its intended maximum distance into a crack in the wall, some of 5 said other perforations will be spaced a uniform distance from the wall corresponding to the distance between the wall and the uprights of the scaffolding.

7. A fabricated structural-metal bar for 10 use as a putlog for scaffolding, said bar having a horizontal flat face and a vertical web, said bar being provided, at at least one end, with one or more perforations for fastening the bar behind the sheathing of the wall, the 15 bar having also other fastening means so spaced that, whether the bar is extended in through the sheathing or not, some of said other fastening means will be spaced a uniform distance from the wall corresponding 20 to the distance between the wall and the uprights of the scaffolding.

8. A fabricated T-bar for use as a putlog for scaffolding, said bar having a horizontal flat face and a vertical web joined to the center thereof and running longitudinally 25 along the bar, both said flat face and said vertical web being perfectly flat, respectively, throughout their whole length, said bar being provided, at at least one end, with one or more perforations for fastening the bar 30 behind the sheathing of the wall, the bar having also other perforations so spaced that, whether the bar is extended in through the sheathing or not, some of said other perforations will be spaced a uniform distance 35 from the wall corresponding to the distance between the wall and the uprights of the scaffolding.

In testimony whereof, I have hereunto subscribed my name this 30th day of April, 40 1927.

ALBERT N. YOUNG.
